(57) **CLAIM**

The ornamental design for a concrete pulverizer, as shown and described.

DESCRIPTION

FIG. 1 is a front top perspective view of the concrete pulverizer with jaws in a first, closed position;
FIG. 2 is a bottom perspective view of the concrete pulverizer of FIG. 1;
FIG. 3 is a right side view of the concrete pulverizer of FIG. 1;
FIG. 4 is a left side view of the concrete pulverizer of FIG. 1;
FIG. 5 is a front view of the concrete pulverizer of FIG. 1;
FIG. 6 is a rear view of the concrete pulverizer of FIG. 1;
FIG. 7 is a top view of the concrete pulverizer of FIG. 1;
FIG. 8 is a bottom view of the concrete pulverizer of FIG. 1; and,
FIG. 9 is a bottom perspective view of the concrete pulverizer of FIG. 1, showing the jaws in a second, open, position. The broken lines shown in the drawings are for illustrative purposes only and form no part of the claimed design.

1 Claim, 9 Drawing Sheets
